(57) **CLAIM**

I claim the ornamental design for a vest for children, substantially as shown and described.

DESCRIPTION

FIG. 1 is a front elevational view of the exterior of the front portion of a vest for children unattached from the rear portion, with the lower front flap of the pouch shown in a closed position. The front portion is shown separately from the rear portion in FIGS. 1-3 for clarity of illustration.

FIG. 2 is a further front elevational view of the exterior of the design as shown in FIG. 1, but with the lower front flap of the pouch shown in an opened position.

FIG. 3 is an elevational view of the interior of the front portion of the design as shown in FIGS. 1 and 2.

FIG. 4 is a rear elevational view of the exterior of the rear portion of a vest for children unattached from the front portion, with all pockets and flaps thereof shown in an opened position. The rear portion is shown separately from the front portion in FIGS. 4-6 for clarity of illustration.

FIG. 5 is a further rear elevational view of the design as shown in FIG. 4, but with all pockets and flaps thereof shown in a closed position.

FIG. 6 is an elevational view of the interior of the rear portion of the design as shown in FIGS. 4-5.

FIG. 7 is a rear elevational view of a vest for children wherein the front portion shown in FIGS. 1-3 and the rear portion shown in FIGS. 4-6 are attached to one another, and the rear portion wraps to the front, with all pockets and flaps shown in a closed position.

FIG. 8 is a front elevational view of the design as shown in FIG. 7.

FIG. 9 is a right side elevational view of the design as shown in FIGS. 7-8.

FIG. 10 is a left side elevational view of the design as shown in FIGS. 7-9.

FIG. 11 is a left side perspective view of the design as shown in FIGS. 7-10.

FIG. 12 is a right side perspective view of the design as shown in FIGS. 7-11; and,

FIG. 13 is a further perspective view of the design as shown in FIGS. 7-12, but as it would appear when worn.

The partial human figure shown in FIG. 13 is environmental subject matter included to illustrate how the design may appear when worn and forms no part of the claimed design. The remaining broken lines represent stitching that form a part of the claimed design.

1 Claim, 13 Drawing Sheets
